Application April 11, 1940, Serial No. 329,092
In Sweden April 12, 1939

13 Claims. (Cl. 299—67)

My invention relates to dishwashing apparatus. One of the objects of my invention is to provide an apparatus of this type wherein the sprays are caused to move with respect to the dishes in order to improve the washing and rinsing. Another object of my invention is to provide a water pump for the dual purpose of recirculating water through the sprays and causing the aforesaid movement of the sprays. In accordance with my invention rotary movement produced by the pump is translated into straight line, or a combination of straight line and circular movement of the sprays.

Another object of my invention is to provide a single control member for controlling the operation of the motor driving the pump and for controlling the admission and discharge of liquid to the apparatus. In addition, the control member automatically locks and unlocks the cover of the dishwasher so that the latter may be opened only when the apparatus is not operating.

A still further object of my invention is to provide means for automatically lifting the dish-supporting rack when the cover is opened. Preferably this is accomplished hydraulically.

Another object of my invention is to provide the interior of the apparatus with surfaces so formed as to deflect liquid impinging thereon from the sprays against the dishes in order to utilize liquid which would otherwise miss the dishes.

Another object of my invention is to provide means for introducing hot air into the apparatus for the purpose of drying the dishes.

Further objects and advantages of my invention will be apparent from the following description considered in connection with the accompanying drawings, which form a part of this specification, and of which:

Fig. 1 is a cross-sectional view of one embodiment of my invention;

Fig. 2 is a cross-sectional view taken on the line 2—2 of Fig. 1;

Fig. 3 is a cross-sectional view of another embodiment of my invention and is taken on the line 3—3 of Fig. 4;

Fig. 4 is a cross-sectional view taken on the line 4—4 of Fig. 3;

Fig. 5 is a cross-sectional view of the apparatus shown in Figs. 3 and 4;

Figs. 6 through 11 are cross-sectional views showing different positions of a valve 82 shown in Fig. 5;

Fig. 12 is a cross-sectional view taken on the lines 12—12 of Figs. 5 and 13;

Fig. 13 is a cross-sectional view taken on the line 13—13 of Fig. 12;

Fig. 14 is a view of a portion of the inside of the cover of the apparatus shown in Fig. 5;

Fig. 15 is a cross-sectional view taken on the line 15—15 of Fig. 14;

Fig. 16 is a cross-sectional view of a portion of an apparatus similar to that shown in Fig. 3, but showing a modification;

Fig. 17 is a cross-sectional view of a further embodiment of my invention;

Fig. 18 is a cross-sectional view taken on the line 18—18 of Fig. 17;

Fig. 19 is a part of Fig. 17 on a larger scale; and

Fig. 20 is a cross-sectional view taken on the line 20—20 of Fig. 17.

Referring more particularly to Figs. 1 and 2, reference character 10 designates a tank or receptacle which is suspended in an outer casing 11 (see Figs. 1 and 5). A hollow casting 12 is secured in water-tight relation to the lower part of receptacle 10. The receptacle 10 and casting 12 form a casing for the mechanism of the device.

25 Rotatably mounted within casting 12 by means of bearings 13a and 13b is a pump housing 13. Casting 12 is formed with an annular recess 14 with which communicates a water supply pipe 15 and a drain pipe 16. Pump housing 13 is formed 30 with an aperture 17 in alignment with the recess 14 and a passage 18 leads from opening 17 to the central part of the pump chamber 19.

An impeller 20 is mounted on a vertical shaft 21 which is rotatably mounted in the pump housing 13. The impeller is formed with openings 33 adjacent to its hub. The lower end of shaft 21 extends below the pump housing and below the casting 12 and is provided with a belt pulley 22 arranged to be driven by an electric motor 23 through a belt 24. Suitable bearings are provided between the casting 12, pump housing 13 and shaft 21, as well as suitable packings for preventing leakage through the lower end of casting 12.

Impeller shaft 21 is hollow and a valve stem 25 extends therethrough. A valve 26 is secured to the upper end of this stem and is arranged to control flow through a valve port 27 in the upper wall of the pump housing. A strainer 28 50 may be disposed over port 27. A spring 29 is arranged on stem 25 within the impeller shaft so as to urge the stem downwardly, thus tending to maintain the valve 26 closed. A lever 30 pivoted on an arm 31 connected to the casting 12 has one end disposed underneath the stem 25, whereby

pivoting in a clockwise direction of the lever serves to open the valve 26 against the force of spring 29. Lever 30 may be operated directly by the foot or may be provided with a rod 32 extending to the top of the apparatus.

Preferably, the pump housing 13 is provided with vanes 34 arranged around the periphery of the impeller. Extending upwardly from the pump housing near its periphery is a hollow member 35 which constitutes the outlet of the pump. Rotatably mounted on member 35 is a tubular arm 36. The member 35 is formed with a plurality of openings 37 in alignment with the interior of tubular arm 36. Rotatably mounted in the opposite end of tubular arm 36 is a hollow T 38 which is formed with a plurality of openings 39 in alignment with the interior of arm 36. The branches of the T are connected to a rectangular sprayer 40. The sprayer comprises lower horizontal arms 41 extending from either side of the T the entire length of the receptacle 10, a pair of vertical arms 42 which extend to the top of the receptacle, and an upper horizontal arm 43 extending against the top of the receptacle and connecting the vertical arms. All of these arms are provided with openings 44 for emitting small streams of water upwardly and downwardly and sideways.

An arm 45 is secured to tubular arm 36 on the opposite side of member 35 and is provided with a roller 46 at its free end. A fixed straight rail 47 extends across the central part of receptacle 10. A plurality of rollers 48 are rotatably mounted on T 38 so as to engage both sides of rail 47. A pair of fixed guides 49 and 50 are disposed as shown in Fig. 2.

A wire basket 51 is supported within receptacle 10 above rail 47 and above the lower horizontal arms 41 of the sprayer 40. Basket 51 does not extend all the way to the ends of the receptacle, but is spaced therefrom sufficiently to permit the vertical arms 42 to extend between the ends of the basket and the ends of the receptacle.

The top of receptacle 10 is closed by means of a hinged cover 52 provided with a pressure relief valve 53. An air duct 54 extends from the motor 23 upwardly outside of receptacle 10 and communicates with a space 55 formed within the cover 52. This space is provided with openings 56 distributed around its edges. The lower end of duct 54 is arranged to receive hot air which has been heated by being blown through the motor for the purpose of cooling the latter. If desired, an electric heating element may be placed within duct 54 in order to further increase the temperature of the air.

The operation of the above described apparatus is as follows:

Dishes to be washed are placed, preferably edgewise, in the basket 51 and cover 52 is closed. Hot water is admitted through the pipe 15 and the motor 23 is started. The hot water flows into the annular channel 14, through the opening 17 and channel 18 to the lower part of the pump chamber 19. The water flows through the openings 33 in the impeller and completely fills the pump chamber. Rotation of the impeller 20 imparts a rotary motion to this water and increases its pressure. The water is discharged into the member 35, from whence it flows through opening 37 into hollow arm 36 and thence through openings 39 into the T 38 and through the arms of the sprayer 40 and out through the small openings 44 therein.

The rotary motion imparted to the water in

the pump chamber acts upon the vanes 34 of the pump housing and causes this housing to rotate. Inasmuch as member 35 is secured to the pump housing it describes a circular path designated by the broken line 57 in Fig. 2. This movement of member 35 causes the T 38 and the sprayer 40 to travel along rail 47 in a straight line. When the member 35 has rotated through 90° in a counterclockwise direction from the solid line position shown in Fig. 2, the arm 45 is in a position at right angles to that shown and the roller 46 contacts the fixed guide rail 50. Continued rotation of the member 35 causes arms 45 to take the position shown in broken lines in Fig. 2, thus assuring that the T 38 and sprayer 40 continue movement to the right, as the member 35 rotates in a counter-clockwise direction. If the guide rail 50 were not provided, the T 38 and sprayer 40 might start back to the left. When the member 35 reaches a position 180° from that shown in full lines in Fig. 2, the sprayer 40 is at its extreme right hand position and further rotation in a counter-clockwise direction of member 35 causes the sprayer to travel to the left along rail 47. Guide rail 49 assures that the sprayer will continue its travel in this direction and reach the full line position. Movement of the sprayer 40 back and forth across the receptacle assures that the spray emitted therefrom will strike all parts of the dishes and thus completely remove all dirt therefrom.

The water discharged from the jets in the sprayer 40 collects in the bottom of receptacle 10, and after sufficient water has been introduced in this manner, the supply of water through pipe 15 may be shut off and the water within the receptacle recirculated by opening valve 26. Usually, a detergent is introduced into the receptacle and by recirculating the liquid the streams of water emitted from the sprayer 40 carries this detergent with it, thus effectively cleaning the dishes.

After the dishes have been cleaned, they may be rinsed by closing the valve 26 and admitting fresh water through the pipe 15.

After the dishes have been rinsed the receptacle may be emptied by opening the valve 26 and the valve in the waste line 16, the valve 15 in the inlet line being closed. Under these conditions, the water within the receptacle 10 drains through the valve port 27 and through the pump chamber 19 to the passage 18 and through the opening 17 into the annular channel 14. From here it passes out through the drain 16, which is preferably connected to the sewage system.

The dishes may be dried by operating the motor 23 after the receptacle has been drained of liquid. There being no liquid present, none is emitted from the sprayer while the hot air discharged from the motor 23 flows through the duct 54 to the space 55 within the cover. From here it is discharged through the openings 56 and comes in contact with the dishes, thus drying them.

In the embodiment of my invention illustrated in Figs. 3 through 5, the receptacle is designated by reference character 10, to the bottom of which is secured the casting 12. A pump housing 60 includes a vertically extending shaft part 61 which is rotatably mounted in casting 12. An impeller shaft 62 is rotatably mounted within the shaft part 61 and carries at its upper end an impeller wheel 63 located within a pump chamber

64. This chamber is provided with an inlet 65 and an outlet 66. Rotatably secured to the outlet 66 is a hollow arm 67, the arm being secured to the pump housing by means of a bolt 68. Rotatably mounted at the opposite end of arm 67 is a hollow spindle 69 provided with openings 70 in alignment with the hollow interior of arm 67. Spindle 69 supports a ring-shaped sprayer 71 by means of hollow spokes 72. Mounted on the lower solid end of spindle 69 is a gear 73 which is arranged to engage internal teeth on a rack 74. As appears from Fig. 4 this rack is rectangularly shaped with rounded corners. A guide roller 75 is secured to the upper end of spindle 69 and engages the exterior surface of a track 76, which is of the same shape as rack 74. Track 76 may be mounted on the lower part of a wire rack 77 for supporting the dishes.

Rigidly secured to the top of pump housing 60 is a cylinder 150 within which is reciprocably mounted a piston 151. The outer end of this piston contacts a projection 152 extending from one side of hollow arm 67. The interior of cylinder 150 communicates with the pump chamber 64 through a passage 153 formed in a part 154 which is integral with the pump housing. Passage 153 is formed with a shoulder 155, and a ball 156, having a larger diameter than the lower part of the passage below the shoulder, is disposed in the upper part of the passage. A pin 157 is threaded into the lower end of part 154 and serves to prevent the ball 156 from seating on the shoulder 155 and completely closing the passage 153. Pin 157 may be adjusted so as to vary the distance the ball is held away from the shoulder. A similar pin 158 is threaded into the upper end of part 154 and prevents the ball 156 from closing the passage leading into cylinder 150. The arrangement is such that liquid may flow from the pump chamber to the cylinder 150 with less resistance than is offered to flow of liquid in the opposite direction. Pin 157 makes it possible to vary the resistance to flow in said opposite direction.

A conduit 80 is connected to the hot water supply and communicates with the inlet 81 of a multi-position valve 82 (Fig. 5). The outlet 83 of this valve is connected by means of a conduit 84 with a valve chamber 88 in casting 12. The upper wall of valve chamber 88 is formed as a valve port 85 communicating with the interior of receptacle 10. This port may be covered by one or more strainers 86. Located within valve chamber 88 is a valve plate 87, which may close either the end of conduit 84 or the port 85. Valve chamber 88 is in direct communication with the inlet 65 of the pump.

A drain conduit 90 is connected to the casting 12 through a valve 91 (Fig. 5). The valve is arranged to be operated by means of a diaphragm 92. A coil spring 93 tends to hold the valve in open position. Diaphragm chamber 94 is connected by means of a conduit 95 with a port 96 formed in valve 82.

This valve includes a rotatable valve member 97 formed with a passage 98 extending straight through it and a branch passage 99 extending at right angles to and communicating with passage 98. A handle 100 is secured to stem 101 of valve member 97, the handle being located outside of casing 11. Also rigidly secured to stem 101 is a disc 102 (Fig. 12). The periphery of this disc is provided with three deep notches 103, 104 and 105 and with three shallow notches 106, 107, and 108. A pivoted bell-crank lever 109 is provided with a pin 110 which is forced against the periph-

ery of disc 102 by means of a spring 111. The other arm of the bell-crank lever is formed as a latch 112 for engaging a recess 113 formed in the cover 52 of the dishwasher.

5 A mercury switch 114 is pivotally mounted adjacent to disc 102 and is provided with a projection 115 located in the path of travel of the bell-crank lever 109. This switch is in the circuit of the electric motor 23 and, when in the tilted position shown in Fig. 12, opens the circuit and when turned to a horizontal position, the circuit is closed.

Secured to the lower part of receptacle 10 is a cylinder 120. Reciprocably mounted within the cylinder is a plunger 121. The diameter of the plunger is such with respect to the cylinder as to leave an appreciable clearance 122 therebetween. A packing 123 at the top of the cylinder prevents leakage between the cylinder and the plunger at this point. A valve housing 124 (Fig. 5) is associated with cylinder 120 and is formed with an inlet chamber 125 and an outlet chamber 126. Chamber 125 is connected to the water supply line 80 by means of a conduit 127 (Fig. 4) while chamber 126 is connected to an overflow drain 128 by means of a conduit 129. The upper end of overflow 128 communicates with the interior of receptacle 10 just below the level of the sprayer 71. Valve housing 124 is formed with a passage 130 which communicates with the space 122 between the cylinder 120 and the plunger 121. Communication between passage 130 and chambers 126 and 125, respectively, is controlled by means of a valve member 131 mounted on a rod 132. In the position shown in Fig. 5, passage 130 is connected to outlet chamber 125, while being closed from chamber 126. If valve 131 is moved downwardly, it closes the opening from chamber 126 to passage 130, while establishing communication between chamber 125 and passage 130.

The upper end of rod 132 is slidably supported by means of a bracket 133. A spring 134 tends to hold the rod in its uppermost position, that is in the position illustrated in Fig. 5. A pin 135 is carried by rod 132 and extends through the top of the casing 11 adjacent to a hinge 136 by means of which the cover 52 is hinged to the casing. This hinge is provided with a projection 136a which strikes the upper end of pin 135 when the cover is opened, thus depressing the pin and the rod 132.

The upper end of plunger 121 is secured to a frame 137 extending around the interior of receptacle 10. Frame 137 is provided with a plurality of rollers 138 which roll against the interior of the receptacle 10. The dish rack 77 is secured to frame 137.

As shown in Figs. 5, 14, and 15, the interior of the receptacle 10 and the inside of the cover 52 are preferably formed with depressions. The depressions 140 in the sides of the receptacle are preferably formed with spherical upper parts 141 which merge into conical lower parts 142. The recesses 143 in the cover are preferably spherical throughout.

This embodiment operates as follows:

When it is desired to wash dishes, the cover 52 is opened. Projection 136a on hinge 136 strikes pin 135 and moves it and rod 132 downwardly against the force of spring 134. This movement of the rod causes the valve 131 to interrupt communication between discharge chamber 126 and passage 130, and to establish communication between inlet chamber 125 and this passage. Consequently, water under the pressure existing in

the city mains flows from supply pipe 80, through pipe 127 into chamber 125 and thence through passage 130 to the space 122 between the piston 121 and the cylinder 120. This water pressure acts on the lower end of the piston and thus raises it. Upward movement of the piston causes frame 137 to move upwardly, the rollers 138 rolling against the inner walls of receptacle 10. Thus, the wire rack 77 is raised to an elevation at which the dishes may be easily placed thereon, preferably in edgewise position.

Cover 52 is now closed and spring 134 moves the rod 132 to the position shown in Fig. 5, thereby establishing communication between passage 130 and discharge chamber 126. The weight of the frame 137 and the dishes forces piston 121 downwardly, the water being discharged through passage 130 into chamber 126, from where it flows through pipe 129 to the overflow conduit 128.

The valve member 97 of valve 82 is assumed to have been in the off position shown in Fig. 6. In this position the disc 102 is in the position shown in Fig. 12, that is, with the pin 110 on the bell-crank lever 109 engaging the deep notch 104. With the bell-crank lever in this position, the latch 112 does not engage the side of the recess 113 in the cover and thus the cover is unlocked. If the valve handle 100 is now turned a quarter turn in clockwise direction, the valve member is brought to the position shown in Fig. 7. In this position passage 98 in the valve member establishes communication between ports 81 and 83 and consequently water is supplied from conduit 80 to the valve and from the valve through conduit 84 to the chamber 88 in the casting 12 (Fig. 3). The water lifts the valve disc 87, thus closing the port 85. The water flows from the chamber 88 through the inlet 65 into the pump chamber 64.

Turning of the valve handle 100 also turns disc 102 a quarter turn in clockwise direction. This causes the pin 110 on the bell-crank lever 109 to be moved out of the deep notch 104, thus pivoting the bell-crank lever in a counter clockwise direction. This movement of the bell-crank lever causes the latch 112 to engage the cover, thus locking it closed. The bell-crank lever 109 also strikes the projection 115 on mercury switch 114, and tilts the switch to closed position. Pin 110 engages the shallow notch 107 in the disc 102, but the depth of this notch is just sufficient to maintain the parts in the desired position without either unlocking the cover or opening the switch 114.

Closing of the switch 114 causes electric motor 23 to drive impeller 68. This imparts rotary motion to the water in the pump housing, which causes the housing itself to rotate, as described in connection with Figs. 1 and 2. At the same time, water under pressure is discharged through the outlet 66 of the pump to the hollow arm 67, from whence it passes through openings 70, hollow spindle 69, hollow spokes 72, to the sprayer ring 71. From this ring the water is emitted in the form of upwardly directed jets.

Rotation of the pump housing 60 causes the gear 73 to travel along the rack 74, thus causing rotation of the gear. Consequently, the sprayer 71 travels in straight lines around the track, while at the same time being rotated around the axis of spindle 69.

Gear 73 is maintained in engagement with rack 74 by virtue of the fact that roller 75 engages track 76.

At certain points in the travel of the gear 73 around rack 74, the rotating pump housing will apply a force to spindle 69 which is at right angles

to the rack. Force applied in this direction obviously cannot cause movement of the gear along the rack and in order to prevent the apparatus stalling at these points cylinder 150 and piston 151 are provided. Water under the pressure imparted by the pump flows into cylinder 150 through passage 153 and exerts a force against the inner end of piston 151. Thus, the piston is continuously exerting a force against projection 152 on arm 61, which force is at an angle to that imparted to the arm by the rotation of the pump housing. Consequently, when the gear reaches a point on rack 74 where it would stall as aforesaid, the force exerted by piston 151 causes the gear to continue past this dead point.

The piston and cylinder also act as a dash pot to absorb shock when the gear travels around the corners of the track. When this takes place projection 152 forces piston 151 into the cylinder 150. However, due to the resistance to flow of liquid out of the cylinder, which is offered by the ball 156 in conjunction with the shoulder 155, the movement of the piston into the cylinder is retarded.

With the valve 97 in the position shown in Fig. 7 passage 99 establishes communication between passage 98 and valve port 96. Consequently, water under pressure is admitted through conduit 95 into diaphragm chamber 94, thus maintaining valve 91 in the closed position shown in Fig. 5. With the valve in this position, drainage of water from the receptacle 10 into the waste conduit 90 is prevented.

After the apparatus has operated in the above described manner long enough so that the operator believes sufficient water has been admitted into the receptacle 10, the valve 100 is turned 45° in a clockwise direction to the position shown in Fig. 8. With the valve in this position flow of liquid therethrough is prevented. At the same time, pin 110 on bellcrank lever 129 has entered the deep notch 103 in the disc 102, thus unlocking the cover and opening the switch 114. The cover may then be opened to determine whether or not sufficient liquid has been admitted. If more liquid is required, the cover is closed and the valve returned to the position shown in Fig. 7. On the other hand, if there is enough water in the receptacle, the valve is turned to the position shown in Fig. 9. In this position flow of water through the valve from port 81 to port 83 is cut off and consequently no water is supplied through pipe 84 to the pump. However, water pressure is maintained through passages 99 and 98 in the valve member to conduit 95 and therefore drain valve 91 is held closed. With the valve in this position, pin 110 on the bell-crank lever engages the shallow notch 106 in the disc 102, thus locking the cover and closing the switch 114.

Inasmuch as no water is admitted through conduit 84, valve disc 87 drops to its lower position and water in the receptacle 10 flows through valve port 85 to the inlet 65 of the pump. Operation of the pump thus causes the recirculation of water from the receptacle through the sprayer.

After the apparatus has been operated in this manner for a sufficient length of time to thoroughly wash the dishes, valve 97 is turned to the position shown in Fig. 10. In this position communication is established through the passage 98 between the ports 81 and 83 and consequently clean water flows from conduit 84 into chamber 88 and thence to the inlet of the pump. The introduction of water under pressure lifts valve

disc 87, thus closing port 85 and preventing the flow of dirty water from the receptacle to the pump. Therefore, only clean water is emitted from the sprayer and serves to rinse the dishes.

Although water under pressure is not admitted through conduit 95 to diaphragm chamber 94, when the valve is in the position shown in Fig. 10, nevertheless, the water trapped in the diaphragm chamber will serve to maintain the valve closed. However, if the level of the water in the receptacle is raised sufficiently during the rinsing operation, it will overflow through the overflow conduit 128.

After the dishes have been rinsed the valve 97 may be turned to the position shown in Fig. 11, in which position flow of water through the valve is shut off. In this position of the valve, pin 110 engages the deep notch 105 in the disc 102 and thus the cover is unlocked and the switch 118 is open. The operator then opens the cover and, if the dishes have been thoroughly washed and rinsed, leaves the cover open. This causes the frame 137 to be raised, in the manner previously described and the dishes may be removed.

The receptacle may be drained by turning the valve 97 another one-eighth turn from the position shown in Fig. 11, which brings the valve back to the position shown in Fig. 6. In this position port 96 is connected to port 83 and thus the water pressure in the diaphragm chamber 94 is relieved whereupon the spring 93 opens the valve 91. Under these conditions the water drains from the receptacle through the port 85 into the chamber 88, and thence through the valve 91 to drain conduit 90.

During the washing and rinsing operations any of the jets from the sprayer 71 which miss the dishes, impinge upon either the sides or the top of the receptacle. The depressions 140 in the sides are so shaped that the streams of water striking them are redirected back against the dishes. Likewise, the streams striking the depressions 143 in the cover are redirected against the dishes. The combination of conical and spherical surfaces of the depression 140 cause the streams to be turned through an angle of approximately 90°, while the spherical depressions 143 cause the streams to be turned through practically 180°.

In the modification illustrated in Fig. 16 the guide roller 75 as shown in Fig. 3, is replaced by a roller 75a located below the gear 73. This roller engages a track 76a mounted on casting 12. However, the operation of this modification is the same as that previously described and hence need not be repeated.

It will thus be seen that I have provided an improved dishwasher which may be controlled through the manipulation of a single valve so as to fill, wash, rinse and drain, while at the same time starting and stopping the motor. Furthermore, it is impossible to open the cover while the apparatus is in operation. Moreover, opening of the cover automatically lifts the rack containing the dishes so as to make it more accessible for putting in or taking out the dishes, and closing the cover lowers the rack to operating position.

In the embodiment of the invention shown in Figs. 17-20 the washing member, which is here designated by 201, is rotatably journaled by means of a shaft 202 on an arm 203 projecting from the pump casing 60. Both the pump casing 60 and the arm 203, in this embodiment, are

formed by two substantially bowl-shaped halves, an upper part 204 and a lower part 205. The shaft 202 is journaled in a bearing sleeve 206 projecting upward from part 205. A gear wheel 207 is rigidly connected to the lower end of the shaft 202, the teeth of said wheel engaging the teeth of an intermediate gear wheel 208 journaled in part 205. The latter gear wheel engages, in turn, with a stationary gear or track 209 rigidly connected by bolts 210 to the bottom 12 of the container 10 and provided with external teeth. The above-mentioned gear wheels 207, 208 and 209 are arranged beneath the part 205 of the casing. The gear wheels 207 and 208 are protected from below by a washer 211 which is rigidly connected to part 205 and which, together with said part, forms a space 212 in which said wheels rotate. For this purpose the half 205 of the casing is formed with a downwardly directed crown-shaped wall 213 enclosing the whole of the gearing 207-209. If desired, the washer 211 may extend beneath the whole gear which, in such case, is encased.

The pump casing 60 is formed with an annular channel 214. Between the outlet opening 215 of this channel in the sprayer member 201 and a flange 216 (see Fig. 19) connected with this member there is arranged a packing ring 217 made of rubber or other suitable packing material. This packing ring 217, which is tightened in the flange 216 and bears against the opening 215, has two functions, namely to prevent washing and rinsing liquid from leaking from said opening into the container 10, and to prevent 35 grains of sand or other particles from penetrating between the said opening and flange. A similar packing washer 218 with the same function is arranged between the pump casing 60 and the gear wheel 209. For preventing coarser 40 particles from the dishes from entering the washing system two strainers 219 and 220 are arranged in the bottom 12, the upper strainer 220 being provided with a handle 221 so that it can be easily raised.

The bearing sleeve 206 of the sprayer member 201 projects, as shown in Fig. 17, through the outlet channel or opening 215 of the pump casing 204 in such a manner that an annular space 222 for the passage of the liquid from the pump casing to the sprayer member is formed round the sleeve 206. The sprayer member 201 consists of an elongated or oval ring 224 provided with spray jet openings 223 (Fig. 18) and made of tubular material, as well as a likewise tubular bridge 225 which connects two parts by extending across the short diameter of the ring. With the middle part of this bridge, which part, as mentioned, forms, like the oval ring 224, channels for the working liquid of the machine, that is washing or rinsing liquid, the upper end of the pin or shaft 202 is connected.

The embodiment according to Figs. 17 through 20 is similar, as regards the extension of the machine, the circulating device and the rotatable pump casing, in the main with the embodiment described in connection with Figs. 3 and 4; that is the dish container 10 has an unrounded, suitably square shape, and the dishes are carried by a strainer bottom 71. A detail in which the two said embodiments differ from each other, is the clutch between the shaft 62 of the conveyer or pump impeller and the belt pulley 22. In forms of the invention shown in Figs. 1 and 3 this clutch consists of an ordinary jaw-clutch between the shaft 62 and a lower shaft

portion; in the last-mentioned embodiment, on the other hand, a sliding clutch 226 has been provided between the lower end of the shaft 62 and a shaft sleeve 227 connected to the belt pulley 22. This sliding clutch makes it possible, also in this case, to raise the whole of the pump casing with the sprayer device connected therewith out of the container 10 for cleaning purposes. The lower end of the shaft sleeve 227 is closed by an easily removable bottom nut 228, it thus being possible, if necessary, to drain off water from this sleeve.

The dish washing machine shown in Figs. 17-20 works as follows. The inlet 84 of the apparatus is opened, the valve disc 87 being raised by the entering water and pressed against its upper seat 229 beneath the strainer. This causes water to flow into chamber 230 beneath the container bottom 12, thence through the openings 65 to the pump casing 60 and from the latter to the sprayer member 201, through the spray jet openings 223 into the container 10 which is filled to a level with an overflow pipe 231 which is arranged in the container and the upper edge of which is approximately on a line with the lower edge of the sprayer member 201. When this level has been reached, the inlet 84 is closed, the valve disc 87 returning to its lower position to form a tight joint with a lower seat 232. In this case, the liquid passes freely from the container 10 by way of chamber 230 to the pump casing 60.

The motor 23 is started, the pump impeller 63 setting in rotation the mass of liquid in the pump casing, and also imparting a rotary motion to the pump casing itself, as previously described. The pump impeller or conveyer 63 at the same time forces the washing liquid through the sprayer member 201 and the openings 223 against the dishes. The rotation of the pump casing 60 will cause the bearing sleeve 206 rigidly connected with it and rotatably receiving the shaft 202 of the sprayer member 201 to be turned round in a circular path, the radius of which is determined by the distance between the shaft 62 and the turning axis 202 of the sprayer member 201. The washing member 201 itself will, during the said turning motion, rotate around its own axis, but owing to the arrangement of the gearing 207-209, in a direction opposite the direction of rotation of the pump casing 60. This means that the sprayer member will effect a planetary motion. During this motion both corners 233 of the sprayer member 201 will be introduced into the corners of the container 10. The sprayer member, as it were, unrolls itself during its motion along the limiting walls of the container, so that all dishes, no matter where they are placed in the container, will be subjected to an efficient spraying. The said motion of the sprayer member is attained by a ratio of 2 to 1 of the gearing 207-209, so that the ends of the member are alternately introduced into the adjacent corners of the casing. The initial position of sprayer member should, for attaining this synchronization, be so adjusted on mounting that its longitudinal axis extends through one of the corners of the casing and the centre of the pump casing. As soon as the washing operation is completed, rinsing is effected in the manner described in connection with the preceding embodiments.

In the last-mentioned embodiment the radiation surface, that is the surface exposed to the jets of the sprayer member during the operation

of the machine, should have at least four corners, and the sprayer member should be provided with at least one point or one corner. The jet openings of the sprayer member should, in the main, have the same direction as the axis of rotation of the member itself. If desired, the dish container or casing may, in place of the fixed wheel or track 209, be provided with a fixed rim equipped with internal teeth against which rim the gear wheel 207 of the washing member rolls. In this case the intermediate wheel 208 will be unnecessary, as the last-mentioned device will cause the washing member to rotate in a direction opposite to that of the pump casing. Further, the sprayer member may, as mentioned, be provided with only one point or one corner, and if the ratio of gearing between the toothed gear or track rigidly connected to the container and the gear wheel rigidly connected to the washing member is 4 to 1, this single point of the sprayer member will, during the motion of the member in the container, successively penetrate into all four corners of the container. It obviously is not necessary that the parts 207, 208 and 209 should consist of toothed members, as these or corresponding members may also consist of friction members or the like.

Evidently, dish washing machines of the kind shown in the accompanying drawings and described above may also work without pressure water from a conduit, in that the necessary water for both washing and rinsing purposes may be poured into the dish container through its upper opening. In this case the circulation of working liquid in the container is effected exclusively by the conveyor or the pump impeller.

Obviously the details of structure of the dish washing machines described above and shown in the drawings may be changed according to the mechanic's skill, and various types of machine be used without departing from the spirit of invention. Thus, the sprayer member may be arranged directly on the rotatable pump casing, thus taking part in its rotation.

What is claimed:

1. In a dish washing apparatus, a casing, a water pump housing, means for rotatably mounting the housing in the casing, an impeller, means for rotatably mounting said impeller in said housing, means for supplying water to said housing, means for driving said impeller, means on the inside of said housing to induce rotary motion thereof by impingement of water thereon, a sprayer member, means to mount said sprayer member for movement along a linear path, means to supply water to said member from said pump, and means connected between said housing and said member for transforming the rotational movement of the housing into linear movement of said member.

2. In a dish washing apparatus, a casing, a water pump housing, means for rotatably mounting the housing in the casing, an impeller, means for rotatably mounting said impeller in said housing, means for supplying water to said housing, means for driving said impeller, means on the inside of said housing to induce rotary motion thereof by impingement of water thereon, a sprayer member, means to mount said sprayer member for movement along a linear path, means to supply water to said member from said pump, means connected between said housing and said member for transforming the rotational movement of the housing into linear movement of

said member, and means for imparting a rotational movement to said member as it travels along said linear path.

3. In a dishwashing apparatus, a casing, a water pump housing, means for rotatably mounting the housing in the casing, an impeller, means for rotatably mounting said impeller in said housing, means for supplying water to said housing, means for driving said impeller, means on the inside of said housing to induce rotary motion thereof by impingement of water thereon, a hollow arm extending radially from said housing, a sprayer member, means for rotatably mounting said member adjacent to the outer end of said arm, said arm constituting means for supplying water from said pump to said member and for moving said member along a linear path, a track, means for securing said track to said frame, a wheel, and means for securing said wheel to said member concentric to the axis of rotation of said member on said arm, said wheel engaging said track to cause rotation of said member around said axis as the member travels along said linear path.

4. In a dishwashing apparatus, a casing, a housing for a water pump, means to rotatably mount the housing in the casing, an impeller, means to rotatably mount the impeller in the housing, means for supplying water to said housing, means for driving said impeller, means on the inside of the housing to induce rotary motion thereof by impingement of water thereon, a sprayer member, means to mount the sprayer member for movement in a straight line, means to supply water to said member from said pump, and means connected between said housing and said member for transforming rotational movement of said housing into straight line movement of said member.

5. In a dishwashing apparatus, a casing, a water pump housing, means for rotatably mounting said housing in said casing, an impeller, means for rotatably mounting said impeller in said housing, means for supplying water to said housing, a motor for rotating said impeller, means on the inside of said housing to induce rotary motion thereof by impingement of water thereon, a stationary track, a sprayer member, means for mounting said member to move along said track, means for supplying water from said pump to said member, and means driven by said rotating housing for moving said member along said track.

6. In a dishwashing apparatus, a casing, a water pump housing, means for rotatably mounting said housing in said casing, an impeller, means for rotatably mounting said impeller in said housing, means for supplying water to said housing, a motor for rotating said impeller, means on the inside of said housing to induce rotary motion thereof by impingement of water thereon, a stationary track, a sprayer member, means for mounting said member to run along said track, and a hollow connecting rod pivotally connected to said member and to said housing adjacent to its periphery for conveying water from said housing to said member and for causing said member to move along said track when said housing rotates.

7. In a dishwashing apparatus, a casing, a water pump housing, means for rotatably mounting said housing in said casing, an impeller, means for rotatably mounting said impeller in said housing, means for supplying water to said housing, a motor for rotating said impeller, means on the inside of said housing to induce rotary

inside of said housing to induce rotary motion thereof by impingement of water thereon, a stationary straight track having its center in line with the center of rotation of said housing, a sprayer member, means for mounting said member to run along said track, and a hollow connecting rod pivotally connected to said member and to said housing, said rod being pivoted to said housing at a point spaced from the center of rotation thereof a distance equal to the length of the connecting rod, whereby rotation of said housing causes said member to run back and forth along said track with a travel in each direction thereof equal to four times the length of said rod, said hollow rod serving to convey water from said housing to said member.

8. In a dishwashing apparatus, a casing, a water pump housing, means for rotatably mounting said housing in said casing, an impeller, means for rotatably mounting said impeller in said housing, means for supplying water to said housing, a motor for rotating said impeller, means on the inside of said housing to induce rotary motion thereof by impingement of water thereon, a stationary endless track, a sprayer member, means for mounting said member to travel along said track, means for supplying water from said pump to said member, and means driven by said rotating housing for moving said member along said track.

9. In a dishwashing apparatus, a casing, a water pump housing, means for rotatably mounting said housing in said casing, an impeller, means for rotatably mounting said impeller in said housing, means for supplying water to said housing, a motor for rotating said impeller, means on the inside of said housing to induce rotary motion thereof by impingement of water thereon, a stationary track, a sprayer member, means for mounting said member to travel along said track, a wheel, means for securing said wheel to said member in a position to engage said track to thereby rotate said member, a conduit member pivotally connected to said pump housing and to said member for supplying water from said pump to said member, and means driven by said rotating housing for moving said member along said track.

10. In a dishwashing apparatus, a casing, a water pump housing, means for rotatably mounting said housing in said casing, an impeller, means for rotatably mounting said impeller in said housing, means for supplying water to said housing, a motor for rotating said impeller, means on the inside of said housing to induce rotary motion thereof by impingement of water thereon, a stationary endless substantially rectangular track, a sprayer member, means for mounting said member to travel around said track, a conduit member pivotally connected to said pump housing and to said member for supplying water from said pump to said member, means driven by said rotating housing for moving said member along said track, a wheel, means for securing said wheel to said member in a position to engage said track for rotating said member, whereby the motion of said member is a combination of circular and straight line motions.

11. In a dishwashing apparatus, a casing, a water pump housing, means for rotatably mounting said housing in said casing, an impeller, means for rotatably mounting said impeller in said housing, means for supplying water to said housing, a motor for rotating said impeller, means on the inside of said housing to induce rotary

motion thereof by impingement of water thereon, a pair of parallel endless tracks, a sprayer member, means for mounting said member to travel between said tracks, means for supplying water from said pump to said member, and means driven by said rotating housing for moving said member along said tracks.

12. In a dishwashing apparatus, a casing, a water pump housing, means for rotatably mounting said housing in said casing, an impeller, means for rotatably mounting said impeller in said housing, means to admit water to said housing, means to rotate said impeller, means on the inside of said housing to induce rotary motion thereof by impingement of water thereon, a stationary rectangular track, a sprayer member, means for mounting said member to travel around said track, a hollow arm pivotally connected to said housing and to said member for conveying water from the pump to said member and for moving said member around said track in response to rotation of said housing, and means for resisting sudden pivotal movement of said arm with respect to said housing as said member travels around a corner of said rectangular track and for continuously imposing a force acting to cause pivoting in the opposite direction.
